his Attorney

UNITED STATES PATENT OFFICE.

AUGUST SONNIN KREBS, OF WILMINGTON, DELAWARE, ASSIGNOR TO KREBS PIGMENT & CHEMICAL COMPANY, OF NEWPORT, DELAWARE, A CORPORATION OF DELAWARE.

APPARATUS FOR CALCINING CRUDE LITHOPONE AND OTHER MATERIALS.

Original application filed April 14, 1923, Serial No. 632,045. Divided and this application filed June 21, 1924. Serial No. 721,436.

My invention relates to apparatus for calcining crude lithopone in carrying out the method of calcination which forms the subject matter of my application filed April 1923, Serial Number 632,045 of which this application is a division but while especially adapted to this use the apparatus can obviously be employed for the calcination of other materials.

In the manufacture of lithopone, purified liquors or solutions of barium sulphide and zinc sulphate are brought together in the precipitating or strike vats in the proper proportion and under proper conditions to produce a mixed precipitate of barium sulphate and zinc sulphide, which, after washing and more or less complete drying, constitutes what is known as crude lithopone.

Long experience in the manufacture of lithopone by old methods and apparatus and protracted experiments and tests with new methods and apparatus has demonstrated that a uniformly excellent product depends very largely on the conditions existing during the calcination of the crude lithopone which must be such that the mass under treatment in all its parts is uniformly heated and maintained at the necessary or desirable calcining temperature for a necessary period and these conditions have been found to require that the mass while being raised to and maintained at the necessary temperature should be constantly tumbled and mixed so that no portion remains in constant contact with or fixed relation to the walls of the furnace chamber and all portions are exposed to the same heating conditions. It has also been found that for uniform good results it is highly desirable that the mass under treatment should for the most part be held out of contact with the furnace walls and for this and other reasons be maintained in a comparatively thick bed or layer in the furnace and for this and other reasons it has been found advisable to maintain in the rotating approximately horizontal muffle, which it is preferred to use, a charge approximately half the cubic capacity of the muffle. In a rotating muffle

through which the lithopone is fed this condition is conveniently maintained by providing the muffle with a centrally located outlet orifice of small diameter at its outer end. A further object of my invention is to prevent the adherence of particles of lithopone to the walls of the muffle furnace. Even where the muffle consists of a metal tube with smooth or unpolished inner walls there is a tendency for particles of lithopone to adhere to the wall, and consequently not mix with the bulk of the tumbling charge, consequently such particles become overburned and moreover such adhering particles tend to promote the adherence of other particles and cause the formation of overburned crusts. It has been found that the adherence of lithopone particles to the furnace wall can be prevented by causing vibrations to occur in the walls of the metal muffle at comparatively short intervals, such vibrations shake loose the adhering particles and insure that all parts of the charge shall be calcined under similar and the best conditions.

Another object of the invention is to provide a means for calcining lithopone by which the lithopone after having been raised to the necessary or desirable temperature is permitted to soak in its own heat for a period before its discharge from the muffle, the lithopone being tumbled during this soaking period as it is during the heating up period.

Still another object of the invention is to provide for the cooling of the calcined lithopone before it is discharged from the muffle or an extension of the muffle, so as to lessen the tendency to form zinc oxide on the exposure of the hot lithopone to the air.

The nature of the invention will be best understood as described in connection with the drawing in which—

Figure 1 is a longitudinal sectional elevation of the improved furnace and

Figure 2, a cross section on line 2—2 of Fig. 1, illustrating a convenient device for periodically rapping the metallic muffle to cause vibration in its walls.

Fig. 1, illustrating a convenient device for periodically rapping the metallic muffle to cause vibration in its walls.

A is the heating furnace, B an oil jet. C, C, walls supporting rollers C' which in turn support the tubular muffle D, through the metallic ring or tires E, E. F is an extension of the muffle C lying outside of furnace A, and having a heat insulating jacket F'. G is a delivery orifice centrally located in the end of the muffle tube and of small diameter. H is a hopper having a tubular 10 delivery spout H' in which works a conveyor I, the shaft I' of which has a sprocket wheel I² secured to it. J is a sprocket wheel secured to the muffle D. K is a driving shaft having sprockets K' and K² which, 15 through chains L and L', drive sprockets I' and J. M is a lever pivoted on shaft K carrying on its free end a weighted roller M' which registers with the lifting cam N secured to the muffle, as shown in Fig. 2.

O is an air cooled muffle extension having external ribs O' and a centrally located restricted discharge opening g. P is a belt conveyor for carrying away the calcined lithopone. Q and Q' are thermocouples. R 25 indicates the level of the lithopone in the muffle.

In operation the crude lithopone is charged into the hopper H and fed from this hopper into the receiving end of the rotating muffle D by the action of the conveyor indicated at I. The construction at the receiving end of the muffle is such as to exclude air. The muffle D is kept in constant rotation by the described mechanism and 30 may be slightly inclined toward its outer end to facilitate the travel of the lithopone through it. As the lithopone travels through the muffle it is gradually raised to proper calcining temperature which it is 35 preferred to maintain moderately low, say between 550° and 750° F., although it is feasible to use somewhat lower temperatures and a temperature of as high as 900° C. or thereabouts may be employed under some 40 circumstances. The time of treatment will naturally vary with the temperature to which the lithopone is raised but within the range of temperatures preferred the period of calcination will be in the neighborhood 45 of from fifty to twenty-five minutes. The lithopone is maintained in the rotating muffle in a comparatively deep layer or bed, approximating half the cubic capacity of the muffle and this is best accomplished by 50 providing the delivery end of the muffle with a centrally located delivery orifice of relatively small diameter, as indicated at G. The exact proportion and volume of the lithopone to the cubic capacity of the muffle 55 is not at all important so long as a bed or layer of substantial thickness is maintained.

The lithopone under treatment is, in the apparatus shown, constantly stirred and tumbled by the rotation of the muffle and 60 this tumbling action is of great importance

in securing substantial uniformity of condition and exposure to heat of the whole mass of lithopone under treatment.

The tendency of particles of lithopone to adhere to the walls of the muffle and become overburned is overcome by causing frequent vibrations in the walls of the metallic muffle and a convenient device for striking frequent periodical blows causing such vibration is the weighted lever M which is raised by the cams N and periodically allowed to fall upon the muffle D.

I have, as already stated, discovered that material advantages are secured by permitting the lithopone after it is raised to the desired calcining temperature to soak in its own heat for a period before its final delivery out of the muffle. Such a heat soaking of the lithopone is provided for in the apparatus shown by the muffle attachment 85 F having a heat insulating jacket F' which is attached to the muffle outside of the furnace A so that, after being raised to the proper temperature the lithopone in the extension F is permitted to soak in its own heat while being constantly agitated and tumbled as it is in the muffle itself.

It is, I believe, advantageous in calcining lithopone in a muffle of whatever construction and mode of operation that the lithopone should be cooled to some material degree before it is exposed to the air and in effect before it escapes from the atmospheric conditions existing in the muffle. This I provide for by attaching to the end of the muffle a cooling extension indicated at O which, as shown, is intended to be air cooled and provide ribs O' but which, of course, can be cooled in any convenient way. This extension, as shown, is secured to the end of the extension F and rotates with the muffle and is provided with a centrally located delivery orifice g of small diameter so that the conditions as to tumbling and thickness of the layer are maintained in this extension. In the construction shown the small delivery orifice G or g insures not only that a properly deep bed of lithopone should be maintained but also provides against the entrance of air at the delivery end of the muffle and its extensions, a constant upward current of gas and vapors generated in the muffle passing through the small delivery orifices.

Having now described my invention, what I claim as new and desire to secure by Letters Patent, is:

1. A furnace for calcining crude lithopone and other material having a horizontal rotatable tubular muffle chamber and means for feeding lithopone through said muffle chamber in combination with means for externally heating said muffle chamber located so as to apply heat to the front portion thereof but not to the rear portion ad-

jacent the delivery orifice and a heat insulating cover for the rear unheated end of the muffle tube.

2. A furnace for calcining crude lithopone and other material comprising a rotatable cylindrical muffle having means for feeding crude lithopone at one end and a centrally located discharge opening at its

other or delivery end of small diameter as compared with that of the cylindrical muffle and an externally cooled cylindrical muffle extension secured to the discharge end of the muffle and having also a centrally located discharge opening of small diameter.
